UNITED STATES PATENT AND TRADEMARK OFFICE
CERTIFICATE OF CORRECTION

PATENT NO. : Des. 348,813
DATED : July 19, 1994
INVENTOR(S) : Gary A. Klein

It is certified that error appears in the above-identified patent and that said Letters Patent is hereby corrected as shown below:

ON THE TITLE PAGE

In column 2, line 5, under "DESCRIPTION" delete "FIG." and substitute --FIG.--.

In column 2, line 7, under "DESCRIPTION" after "and" delete --,--.

Signed and Sealed this

Twenty-eight Day of February, 1995

Attest:

BRUCE LEHMAN

Attesting Officer

Commissioner of Patents and Trademarks
